UNITED STATES PATENT OFFICE.

MARTIN LOGAN, OF NEW YORK, N. Y.; MARGARET LOGAN ADMINISTRATRIX OF SAID
MARTIN LOGAN, DECEASED.

NON-REFILLABLE BOTTLE.

1,145,325.

Specification of Letters Patent.

Patented July 6, 1915.

Application filed March 4, 1911, Serial No. 612,239. Renewed January 5, 1915. Serial No. 666.

To all whom it may concern:

Be it known that I, MARTIN LOGAN, a citizen of the United States, and a resident of New York, county and State of New York, 5 have invented certain new and useful Improvements in Non-Refillable Bottles, of which the following is a full, clear, and exact description.

This invention relates more particularly 10 to bottles having automatic means within the bottle neck to prevent the same from being refilled after the bottle or other container is empty or partly empty.

One object of the invention is to provide 15 a bottle having means within the bottle neck which is so constructed that the liquid may readily flow from the bottle or container, but which becomes sealed if an attempt is made to refill the bottle through the mouth 20 of the bottle neck, and which means is so constructed that it may be readily applied to a bottle without materially increasing the cost of its manufacture.

Another object of the invention is to provide 25 simple and efficient means which will prevent tampering from the outside of the bottle with the means forming the seal which prevents the refilling of the bottle.

A further object of the invention is to provide 30 simple means for holding a ball valve within the bottle neck and for preventing the same from moving too far away from its seat, and at the same time to provide 35 means which may be readily applied to a bottle.

With these and other objects in view, the invention will be hereinafter more particularly described with reference to the accompanying drawings, which form a part of 40 this specification, and will then be pointed out in the claim at the end of the description.

In the drawings, Figure 1 is a fragmentary vertical section of a part of a bottle 45 with one form of my invention applied thereto. Fig. 2 is a plan view of the bottle neck. Fig. 3 is a sectional plan through the bottle neck taken on the line III—III of Fig. 1. Fig. 4 is a section taken on the line 50 IV—IV of Fig. 1; and Fig. 5 is a section taken on the line V—V of Fig. 1, showing the valve which serves to seal the bottle against refilling.

The body 10 of the bottle or other con-

20 of the device 21, and which as soon as 55 tainer has a neck 11 and under the neck 11 may be a shoulder 12 forming a lower support for a guide element 13. This element 13 may be cylindrical in form and of glass or other material and may be independent 60 of the bottle neck or formed as a part thereof, as desired. This guiding element 13 when separate has a sealing disk 13^a of cork or other material and a seat portion 14 against which is adapted to rest a ball or 65 spherical valve 15 serving to close the opening 16 to prevent liquid from passing from the neck into the body of the bottle, or to permit the liquid to flow from the body 10 when the valve 15 is out of engagement 70 with its seat. The element 13 has spaced guiding ribs 17 which taper from the upper portion thereof to the lower portion, and on account of the ribs, the space within the device or element 13 will be larger at the 75 bottom adjacent to the seat than at the top, the top being of sufficient size to permit the ball or other valve 15 to enter the device or element 14. The enlarged opening at the bottom of the element 13 serves to permit 80 the valve when unseated to fall to one side, and owing to the inclination of the ribs 17, the said valve is less likely to move farther than is necessary or desirable for the proper flow of the liquid or material whatever its 85 nature may be that is contained within the bottle.

A weight element 18 which may be larger than the valve element 15 is provided, and this weight element is large and heavy 90 enough to hold the valve 15 to its seat, and arranged above the weight element 18 are a plurality of elements 19. As shown, these elements 19 are three in number and are so arranged that they have independent movement about the upper portion of the weight element and serve as retaining means therefore and prevent too great a movement of the weight element 18, as one or more of the elements 19 when the bottle is tilted will 95 engage against the lower surface 20 of an element or member 21. It will be seen, therefore, that the valve 15 will have a limited outward movement when the bottle is tilted to permit the liquid to flow into the 100 bottle neck, and that this movement is secured through the weight 18 and the elements 19 by engagement with the lower end 105 of the device 21.

the bottle is placed in a vertical position, or partly vertical, the weight element 18 will again force the valve 15 to its seat.

The member 21 is tubular in form and projects inward through the bottle mouth, and said tubular member has its lower end closed and its upper end provided with a flange 22 under which is a cork disk 23 or other means which may be employed to 10 seal the member 21 within the bottle neck. This member 21 has a plurality of lateral and peripheral slots or openings 24 which may be arranged in any desired way and of any desired number, the purpose of said 15 slots being to permit a free flow of the liquid from the bottle neck, but owing to their position, will prevent a wire or other tool from being forced through the bottle mouth or through one or more of the openings to 20 tamper with the valve 15 and hold it from its seat.

The outer end of the tubular member 20 may receive a cork 25 to prevent the 25 liquid from flowing from the bottle, and above the flange 22 may be provided a suitable seal 26, as wax or other material, on which may be indicated the name of the manufacturer, if desired, and around the 30 bottle neck may be arranged a tin foil or other means which will entirely inclose the means which prevents the bottle from being refilled so that said means cannot be seen unless the tin foil is removed.

It will be understood that the liquid after 35 being once poured into the bottle neck will remain there until poured therefrom; and it will be further understood that the elements 15, 18 and 19 may be of any desired shape and of any suitable material.

Copies of this patent may be obtained for five cents each, by addressing the "Commissioner of Patents, Washington, D. C."

From the foregoing, it will be seen that a 40 simple and efficient bottle is provided whereby the liquid after being removed from the bottle cannot be refilled through the mouth thereof; that said means is very simple in construction and may be readily applied 45 to the bottle; and that said means does not materially increase the cost of manufacture of the bottle.

Having thus described my invention, I claim as new and desire to secure by Letters Patent:—

In a non-refillable bottle, the combination with a body including a neck, of a circular shoulder formed on the body at the juncture of the neck, a washer supported on the 55 shoulder adjacent an opening connecting the body with the neck, a valve guide supported on the washer, a cylindrical valve seat formed within the guide by enlarging the lower portion of the said guide to form 60 an inwardly projecting ledge portion, a ball valve lying wholly within the guide and normally reposing on the seat, a series of longitudinally upwardly and inwardly inclined ribs, relatively spaced apart and projecting from the side of the said guide to be engaged by the valve for retarding the forward movement thereof when the body is tilted, and a ball weight loosely arranged 65 in the said neck and adapted to engage the valve to normally hold the same on the said seat and within the said guide.

This specification signed and witnessed this first day of March, A. D. 1911.

MARTIN LOGAN.
